CARTRIDGE FERRULE TYPE
REFILLABLE FUSE

John B. Glowacki, Chicago, Ill.

Application March 26, 1934, Serial No. 717,320

20 Claims. (Cl. 200—131)

This invention relates more particularly to a cartridge ferrule type refillable fuse comprising a barrel or shell having a plurality of flat outer surfaces adapted to prevent rolling of the fuse when placed on a flat surface and furthermore serving as a means for holding the fuse casing when end caps are secured on the ends thereof. The improved fuse includes removable end caps provided with combustion or gas outlet chambers filled with coils of screening or with superimposed layers of screen discs secured in place by means of multiple grooved contact bushings secured in the caps in position to afford contacts for the ends of a fuse element held in position within the fuse casing by means of suitable casing end plates.

It is an object of this invention to provide a cartridge ferrule type refillable fuse including a molded casing having an integral closure plate at one end and a removable closure plate at the other, said casing having the end sections thereof externally threaded for the reception of internally threaded end cylindrical caps the inner ends of which contact the multiple surfaced main body portion of the casing.

It is also an object of this invention to provide a cartridge ferrule type fuse wherein the casing has the outer peripheral surface thereof multiple sided to obviate rolling of the fuse and facilitating gripping of the fuse for the assembly of the removable and replaceable parts of the fuse.

Another object of the invention is the provision of an improved type of cartridge ferrule type fuse including a molded casing having a permanent closure plate at one end and a removable closure plate at the other, said casing having the end portions thereof externally threaded to the ends of the multiple sided intermediate portion of the casing.

It is furthermore an object of this invention to provide an improved cartridge ferrule type fuse including a multiple sided casing having removable metal end caps provided with gas outlet chambers filled with a plurality of layers of screening or perforated material for thoroughly breaking up the products of combustion resulting from the blowing of a fuse element in the fuse casing.

A further object of the invention is the construction of a fuse including a molded casing having screw sleeves partially imbedded in the end portions thereof for the reception of removable metal end caps containing means for thoroughly breaking up the products of combustion

resulting from the blowing of a fuse element in the casing.

Another object of the invention is to provide a cartridge ferrule type refillable fuse having end caps containing grooved bushing units having screening means therein for breaking up the products of combustion resulting from the blowing of a fuse element within the fuse.

A further object of the invention is the construction of a fuse including a casing having chambered end caps removably engaged thereon, said caps having screen carrying contact bushings engaged therein, with said bushings provided with flanges having the outer surface thereof provided with a network of gas escape grooves communicating with the screening means within the end caps of the fuse.

It is an important object of this invention to provide an improved type of cartridge ferrule type refillable fuse including a molded casing having the major portion of the body thereof provided with exterior flat surfaces and having the ends of the casing formed for the removable reception of chambered end caps containing flanged members or plates provided with a network of intercommunicating gas outlet grooves for permitting the products of combustion resulting from the blowing of a fuse to enter the chambered caps and be disseminated by superimposed layers of screening in the end caps of the fuse.

Other and further important objects of this invention will be apparent from the disclosures in the specification and the accompanying drawings.

The invention (in a preferred form) is illustrated in the drawings and hereinafter more fully described.

On the drawings:

Figure 1 illustrates an elevational view of a cartridge ferrule type refillable fuse embodying the principles of this invention.

Figure 2 is a longitudinal central section of the fuse with parts shown in elevation.

Figure 3 is an enlarged fragmentary longitudinal section of the fuse, with the fuse element omitted, and with the enclosed mechanisms in the fuse caps illustrated in section.

Figure 17 is a fragmentary longitudinal detail section through a modified form of fuse casing, of a molded type, including flanged screw thimbles molded around the reduced end sections of the casing.

Figure 18 is a fragmentary side elevation of one end of the modified form of fuse casing shown in Figure 17 showing means for holding the metal thimble secured in position against rotation.

Figure 19 is an end view of the open end of the fuse casing shown in Figure 17.

Figure 20 is an enlarged fragmentary elevational view of another modified form of fuse casing with parts shown in section and including threaded thimbles for engagement on the reduced threaded ends of the casing, and also showing means for holding the thimbles in place against rotation on the casing.

Figure 21 is an end view of the open end of the fuse casing shown in Figure 20.

Figure 22 is a diametrical section of the closure thimble for closing one end of the casing shown in Figure 20.

As shown on the drawings:

The improved cartridge ferrule type refillable fuse of this invention comprises a tubular body or casing constructed of a molded insulating material. The molded casing is designated by the reference numeral 1 and has the major portion of the exterior thereof formed with a plurality of longitudinally directed flat surfaces 2 which serve as a means for preventing rolling of the fuse when placed on a flat surface, and also serving as a means whereby the fuse casing may be readily gripped and held against rotation during the assembly of the fuse. One end of the fuse casing 1 is reduced in diameter to form an exteriorly threaded sleeve or end section 3 having an integral end closure plate 4 provided with a pair of oppositely positioned outlet passages or openings 5 and with a fuse element receiving slot 6 positioned off center. The opposite end of the molded casing 1 is also reduced in diameter to form an exteriorly threaded open sleeve or end section 7 the end of which is provided with a ring recess

8 having a guide or centering rib or bead 9 forming an integral part of the end section 7 and projecting into the circular recess 8.

The open end of the casing end section 7 is adapted to be removably closed by means of an insulation closure plate or disc 10 provided at its outer end with a stop flange or rim 11 adapted to engage the outer end of the end section 7 to limit the insertion of the closure disc 10 into the open end of the casing. The peripheral surface 10 of the closure disc 10 is provided with a transverse groove or slot 12 (Figures 14 and 15) to register with the guide rib or bead 9 so that the closure disc can only be inserted in a single predetermined position with respect to the end of 15 the casing. The closure disc 10 is provided with a pair of oppositely positioned gas outlet openings or passages 13. Also provided in the closure disc 10 below the center line thereof is a fuse element receiving slot 14.

Engaged diagonally through the fuse casing 1 is a fuse element 15 having pairs of oppositely positioned notches 16 in the longitudinal margins thereof. Irregular or I-shaped openings 17 are provided in the strip 15 between the pairs of 25 marginal notches 16 thereby forming fusing strips 18 between the ends of the I slots and the notches 16. The fuse strip 15 is also provided with pairs of marginal notches 19 near the end portions of the fuse strip forming reduced fusing strips 20 30 which are wider than the fusing strips 18 and divide the main body of the fuse strip from the end portions 21. The end portions of the fuse element are adapted to be bent or deflected along the dotted line 22 leaving end flaps 23 which are 35 adapted to be deflected outwardly in opposite directions to be disposed against the outer faces of the casing end members.

Removably threaded on each end section 3 and 7 of the fuse casing is a metal cap 24 which is 40 internally threaded for engagement with the threads on the casing end section. The open end of the cap 24 is provided with a beveled end surface which is adapted to tightly engage against a beveled surface at the end of the main body 45 section of the casing 1, when the cap is in its innermost position. Each end cap 24 is provided with a chamber 25 between the outer surface of the end closure plate of the fuse casing and the inner wall of the closure plate 26 of the end cap. The cap end plate 26 is provided with a centrally disposed boss or hood 27 provided with a diametrical slot 28 to receive a tool for tightly screwing the cap in position upon the threaded end section of the fuse casing. The hood 27 is 55 provided with a central outlet aperture or opening 29 which communicates with a chamber provided in the hood 27. The end plate 26 of the cap is provided with a central opening which registers with the chamber in the hood 27, and said end plate 26 has the inner peripheral edge thereof cut away to provide a beveled surface leaving a circular escape groove 30 between the cap chamber 25 and the chamber within the cap hood 27.

Rigidly secured within the closed end of each of 65 the fuse caps 24 is a bushing unit comprising a sleeve 31 provided on the exterior peripheral surface with a straight knurled section 32 the straight rib portions forming the same adapted to cut into the inner surface of the hood chamber 70 27 to securely hold the bushing unit in place. The bushing sleeve 31 is provided with a plurality of spaced vent apertures or openings 33 which communicate with the groove 30 formed within the cap. The inner end of the bushing sleeve 31 is 75

closed by means of an integral contact head or plate 34 provided with a peripheral groove for receiving an inner peripheral flange of an insulation ring or flange plate 35 through which the 5 contact head 34 of the metal bushing projects as clearly illustrated in Figure 3. The insulation flange or ring 35 has the outer surface thereof provided with a network of communicating grooves 36 as clearly illustrated in Figure 5, and said 10 grooved surface fits tightly against the inner surface of the end wall or plate 26 of the fuse cap with the grooves 36 communicating with the ring groove 30 to establish communication between the cap chamber 25 and the chamber within the 15 bushing sleeve 31. Seated within the chamber of the bushing sleeve 31 is a filling of porous material such as a spiral roll or coil of wire screening 37. A modified form of porous filling may be substituted for the wire coil 37 and may consist 20 of a plurality of perforated plates or wire screen discs 38a (Figure 6) which may be superimposed upon one another to form a stack of wire screen discs sufficient to fill up the chamber within the bushing sleeve 31.

25 With the fuse assembled as illustrated in Figure 2 the end flaps 23 of the fuse element are tightly clamped between the ends of the fuse casing and the contact plates 34 forming part of the contact bushing units engaged in the fuse end caps 24. 30 By gripping the fuse casing around the flat sided body portion, the fuse may be securely held to permit the end caps 24 to be tightly threaded into position upon the end sections of the fuse casing.

When the improved cartridge ferrule type re- 35 fillable fuse is connected in an electrical circuit the connection is established between the end caps and the fuse element to close the circuit. When a short circuit occurs or when an excess amount of current passes through the fuse the fuse element 40 will blow at the fusing strips 18 permitting the middle section of the fuse strip to drop out to break the circuit. The gases and other products of combustion resulting from the blowing of the fuse are permitted to escape from the fuse casing 45 through the vent openings 5 and 13 in the end closure plates of the casing into the cap chambers. 50 From the chambers 25 the products of combustion and gases are permitted to escape through the network of grooves 36 in the insulation flanges or plates 35 through the hood grooves 30 and the bushing sleeve apertures 33 into contact with the porous material or wire coil filling 37 which acts to thoroughly break up the products of combustion and reduce the velocity of the gases which are 55 eventually permitted to find their way through the labyrinth of passages and openings in the wire filling until the gases escape through the outlet openings 29 provided in the hoods 27 formed on the closed ends of the fuse caps 24.

60 In the modified form of fuse illustrated in Figure 7 the construction of the casing and end caps is substantially the same as that hereinbefore described with the exception that the end caps are each provided with a modified form of a contact bushing unit.

The modified form of bushing unit of Figure 7 comprises a bushing sleeve 38 having a plurality of spaced outlet or vent openings 39 provided therein to communicate with the groove 30 of the 70 fuse caps. The outer peripheral surface of the bushing sleeve 38 is provided with a ring of straight knurling, similar to that illustrated in Figure 2, to permit the bushing sleeve to be tightly driven into the hood portion 27 of the fuse cap. 75 The bushing sleeve 38 is filled with a filling of

porous material such as a coil of wire screening 40 or a stack of superimposed wire discs similar to the type illustrated in Figure 6. Integrally formed on the inner end of the bushing sleeve 38 is a closure plate or disc 41 having formed in the 5 outer face thereof a network of ventilating or escape grooves or passages 42 similar to the arrangement illustrated in Figure 5. Integrally formed on the middle portion of the inner side of the bushing closure plate 41 is a contact boss 10 43 adapted to be clamped against the deflected end flaps 23 of a fuse element 15 to clamp the same tightly against the end closure plates of the fuse casing. Securely engaged around the boss 43 and contacting the inner face of the closure 15 plate 41 is an insulation ring or washer 44 which serves as a means for preventing the products of combustion escaping from the fuse casing from adhering to the metal closure plate 41 to clog up the interior of the fuse cap and thereby prevent 20 proper escape of the gases resulting from the blowing of a fuse element.

Figure 8 illustrates a fragmentary portion of another fuse constructed similar to the fuse illustrated in Figure 3 with the exception that another modified form of gas disseminating filler unit is enclosed in the fuse caps. In this modified form a porous filling such as a coil of wire screening 45 is securely packed within the chamber of the fuse hood 27 and is held in place by 30 means of a metal closure plate or disc 46 the outer peripheral surface of which is provided with a straight knurling 47, as illustrated in Figure 16, to permit the closure plate to be tightly driven into the cap chamber 25 to seat against 35 the inner surface of the end plate 26 of the cap. The outer surface of the closure plate 46 is provided with a network of escape passages or grooves 48 which communicate with the ring groove 30 thereby allowing gases and products 40 of combustion from the fuse cap chamber 25 to escape through the knurling 47 and the grooves 48 into the wire filling 45 to be broken up or disseminated before escaping through the outlet opening 29 provided in the hood 27 of the closure 45 cap.

It will be noted that with the various forms of filling units provided in the end caps of the fuse that the products of combustion are thoroughly broken up so that no flames are permitted to escape through the openings in the ends of the fuse through which only the resultant gases of the blowing of a fuse element are permitted to escape at a comparatively slow rate of speed.

Figures 17, 18, and 19 illustrate a modified 55 form of fuse casing molded from an insulation material and comprising an intermediate or main body portion 49 having end sections 50 and 51 of reduced diameter integrally formed on the ends thereof. The exterior of the body portion 49 of the casing is provided with a plurality of adjacently positioned flat surfaces 52 which serve to facilitate tight gripping of the fuse casing during the assembly of the same and furthermore serve as a means for preventing the fuse from 60 rolling when placed upon a flat surface. The end casing section 50 is open at its outer end and is provided with a circular groove 53 into which a guide or stop bead or rib 54 projects. The stop or guide rib 54 is provided for fitting into the 65 recess or groove 12 of the casing end plate 19 of the type illustrated in Figures 14 and 15. The rib or bead 54 insures proper positioning of the fuse element in a predetermined position within the fuse casing.

Molded around the exteriorly threaded end section 50 of the fuse casing 49 is a threaded metal sleeve or thimble 55 having an integral inwardly directed outer flange 56 which seats tightly against the outer end of the fuse casing end section 50. Also integrally formed on the thimble 55 is an outwardly directed inner flange 57 which seats tightly against one end of the main body portion of the sleeve casing 49. As clearly illustrated in Figure 19 of the outer flange 56 of the thimble 55 has a rounded flap 58 integrally formed thereon to fit against the outer end of the guide rib or bead 54.

The end section 51 of the fuse casing is provided with an integral closure plate 59 which is provided with a pair of oppositely positioned vent openings or passages 60 and with a fuse element receiving slot 61 which is positioned off center for receiving one end of a fuse element similar to the arrangement illustrated in Figure 2. Molded around a threaded portion of the casing end section 51 is a threaded metal thimble 62 having an integral inwardly directed outer flange 63 which is imbedded in the material forming the end closure plate 59 of the fuse casing. Integrally formed on the inner end of the threaded thimble 62 is an outwardly directed inner flange 64 which seats tightly against one end of the main body portion of the fuse casing 49.

For the purpose of holding the threaded thimbles 55 and 62 against rotation on the reduced end sections of the fuse casing each of the thimbles has the threaded portion thereof provided with one or more inwardly struck indents 65. The inner flange of each of the threaded thimbles is provided with an indented or deflected portion 66 which is molded into the casing material to assist the indents 65 in holding the thimbles tightly secured in place against rotational movement.

Figures 20, 21, and 22 illustrate another modified form of fuse casing which is constructed of tubular insulation material and comprises a cylindrical main casing body 67 having integrally formed on the ends thereof reduced exteriorly threaded end sections 68 and 69. The outer end of the casing end section 68 is provided with a circular recess or ring groove 70 for the reception of an end closure cap 10 of the type illustrated in Figures 14 and 15.

Threaded onto the exterior of the threaded casing end section 68 is a metal threaded thimble 71 having an integral outwardly directed inner flange 72 which seats tightly against one end of the main body portion 67 of the fuse casing. Integrally formed on the outer end of the threaded thimble 71 is an inwardly directed flange 73 having a centering flap or guide member 74 integrally formed thereon and positioned to the outside of the circular groove 70 to insure positive positioning of the end closure plate 10 so that a fuse element can only be engaged within the fuse casing in a predetermined position similar to the arrangement illustrated in Figure 2. For the purpose of holding the threaded thimble 71 in position against rotation on the end section 68 of the fuse casing the thimble is provided with one or more indents 75 and the inner flange 72 of the thimble is also indented at 76 to obviate rotation of the thimble.

The end casing section 69 has threaded thereon a threaded metal thimble 77 having an inner outwardly directed flange 78 and an outer inwardly directed flange 79 which is imbedded in a molded insulation end plate 80 which is adapt-

ed to seat tightly against the outer end of the casing end section 69. The insulation closure plate 80 is provided with a pair of oppositely positioned vents or outlet openings 81 and with a slot 82 positioned off center for the reception of one end of a fuse element. The threaded thimble 77 is provided with one or more indents 83 which project into the material forming the casing end section 69 to hold the thimble locked against rotation with respect to the casing. The inner flange 78 of the thimble 77 is provided with one or more indents 84 which cut into the end of the main body 67 of the casing to assist the indents 83 in holding the thimble in proper position against rotational movement with respect to the casing.

Attention is called to the fact that in the various forms of fuse casing that the same may be formed of molded material or may be constructed out of tubular stock such as illustrated in Figure 20 and the end sections of the casing may be reduced in diameter and exteriorly threaded for the reception of removable metal end caps such as illustrated in Figures 7 and 8 or the reduced end sections of the casing may have threaded metal 25 thimbles secured thereon similar to the arrangement illustrated in Figures 17 and 20 in which constructions the metal end caps are threaded onto the metal thimbles which are rigidly secured on the casing end sections.

Attention is specifically directed to the fact that in this improved type of refillable cartridge fuse that the main body or casing is completely constructed of insulating material including the casing walls and the end closure walls so that the only metal within the casing proper is the blowable fuse element. All other metal parts of the improved fuse are contained in the fuse end caps. When a fuse element is blown within the fuse casing the hot metal resulting from the blowing or melting of the fusible strips of the fuse element move into contact with the insulating walls of the casing and do not adhere thereto as they would to metallic walls. The resultant hot air and gases pass outwardly through the vent openings in the end plates of the casing into the cap chambers and any hot metal which may find its way into the cap chambers contacting the insulation plates forming part of the bushing unit within the caps becomes cooled and does not adhere to the metal parts to clog up the caps. The gases and hot air entering the cap chambers gradually find their way into the circuitous passages or groove network 36 in the bushing disc and enter the hood portions of the end caps 55 through the grooves 30 and the bushing apertures 33 and engage the porous filling or the wire screening within the end chambers of the caps so that the gases and air are practically cooled off before they issue through the outlet openings 29 60 in the ends of the fuse caps. Tests show that there is only a slow gradual discharge of the practically cooled air and gases from the end apertures of the fuse after the blowing of a fuse element. Any flames which might result from the blowing of a fuse element within the improved fuse are completely destroyed or broken up before they reach the outlet openings 29 in the ends of the fuse caps.

After the blowing of a fuse element the fuse is removed from its support and is held by the body portion, the flat outer surfaces of which permit tight gripping of the fuse to facilitate removal of the end caps 24. After the end caps have been removed the removable end plate 10 of the casing 75

is removed thereby allowing the remaining parts of the blown fuse to be taken out to be replaced by a new fuse element. The end plates of the fuse casing have the fuse element receiving slots 5 formed with straight and inclined surfaces as clearly illustrated in Figures 7 and 17 to facilitate mounting of the fuse element. The partially deflected end 23 of the fuse element is first inserted through the slot in the permanent closed 10 end of the casing until the completely deflected opposite end of the fuse element comes in contact with the outer surface of the closed end of the casing. The removable closure plate 10 is then engaged over the partially deflected end of 15 the fuse element which now projects diagonally through the fuse casing and said closure plate 10 is then inserted in the open end of the casing to close the same thereby properly positioning the fuse element in the diagonal position illustrated 20 in Figure 2 after which the partially deflected projecting end of the fuse element is bent over against the outer surface of the removable closure plate 10. The end caps are now reengaged on the ends of the casing with the contact bushings 25 within the caps clamping the end portions 23 of the fuse element tightly against the end plates of the fuse casing.

The network of circuitous escape passages in the bushing plates disposed within the fuse end caps and the circuitous passages provided by the porous or screen fillings in the chambers of the end cap hoods are instrumental in assuring the destruction of any flames which might result from the blowing of a fuse element within the fuse casing 35 and furthermore serve to reduce the speed of the escaping hot air and gases to such an extent that the gases and air are practically cooled off and are slowly discharged out of the escape openings in the ends of the fuse caps.

It will of course be understood that many 40 details of construction may be varied through a wide range without departing from the principles of this invention and it is therefore not the purpose to limit the patent granted hereon otherwise than necessitated by the scope of the appended 45 claims.

I claim as my invention:

1. A cartridge ferrule type refillable fuse comprising an insulation casing having reduced 50 threaded end sections, an apertured and slotted insulation disc integrally formed on one end of the casing, an apertured and slotted insulation disc removably engaged in the opposite end of the casing, a fuse element in said casing having the ends thereof projecting through the slots in the end discs and bent over to lie against the outer 55 surfaces of said end discs, apertured end caps removably engaged on the reduced threaded end portions of the casing, contact means secured in the end caps and contacting the ends of the fuse element, disc means forming a part of the contact means and having a network of escape passages formed therein, and layers of wire screening retained in the caps by the contact means.

2. A cartridge ferrule type refillable fuse comprising an insulation casing having an apertured and slotted closure disc integrally formed on one end thereof, an apertured and slotted closure disc removably engaged in the opposite end of the casing, grooved and apertured contact cap members 70 removably engaged on the ends of the casing, grooved and apertured contact means in the caps, and coils of wire screening clamped in position between the end caps and the contact means.

3. A cartridge ferrule type refillable fuse com-

prising an insulation casing having the end portions thereof reduced and exteriorly threaded, an apertured and slotted insulation closure disc integrally formed on one end of the insulation casing, an apertured and slotted closure disc removably engaged in the opposite end of the insulation casing, a fuse element engaged in the insulation casing and having the ends thereof projecting through the slotted insulation end closure discs, with the ends of the fuse element 10 bent over and lying flat against the outer surfaces of the closure discs, and contact caps removably engaged on the reduced threaded end portions of the insulation casing and contacting the deflected end portions of the fuse element. 15

4. In a fuse of the class described including in combination an insulation casing comprising an insulation body closed at one end and open at the opposite end, said open end having a groove formed therein, a projection extending 20 into the groove, a grooved insulation closure plate extending into the groove in the open end of the insulation body with the projection registering with the groove in the closure plate to hold the same in a predetermined position, and 25 threaded thimbles secured against movement around the end portions of the insulation body.

5. In a fuse of the class described including in combination a casing comprising an insulation body, a slotted and apertured insulation closure 30 plate integrally formed in one end of the body, a slotted and apertured insulation closure plate removably engaged in the opposite open end of the body, means for insuring the insertion of the removable end closure plate in only a single 35 predetermined position in the open end of the insulation body, threaded metal thimbles engaged around the end portions of the insulation body, and means for holding the threaded thimbles in position against rotation with respect 40 to the body.

6. In a fuse of the class described the combination with an insulation casing, of an apertured cap removably engaged thereon, an apertured contact member secured in the cap, said 45 cap having a groove therein registering with the apertures in the contact member, a screen filling in the contact member, and a plate forming part of the contact member and having a network of air and gas escape grooves formed there- 50 in and communicating with the groove in the cap.

7. A cartridge type fuse comprising an insulation casing having insulation end closure members, metal caps removably engaged on the 55 ends of the insulation casing, grooved contact means secured in the caps adjacent the closed ends of the insulation casing, and coils of wire screening in the caps held in position by the contact means. 60

8. In a fuse of the class described including in combination a cap, a contact means secured therein and having a surface provided with a network of escape grooves, and a screen filling in the cap held in position by the contact means. 65

9. In a cartridge type fuse including in combination a cap, an apertured hood extension formed thereon, an apertured contact member in the cap and projecting into the hood, a plate forming a part of the contact means and 70 having a surface thereof provided with a network of escape grooves, and a screen filling in the apertured contact means and in said hood.

10. In a cartridge type fuse of the class described the combination with a cap having a 75

groove therein, of an apertured hood formed on the cap, a screen filling in the hood, and a contact member secured in the cap and having a surface thereof provided with a network of escape grooves communicating with the groove in the cap.

11. In a cartridge type fuse of the class described an end closure unit comprising a cap having a groove therein, an apertured hood integrally formed on said cap, an apertured contact member in said cap projecting into the hood with the apertures in the contact member registering with the cap groove, a flange on the contact member having a network of escape grooves formed therein and positioned to communicate with the groove in the casing, and a wire screen filling held in position between the apertured contact member and said apertured hood.

12. A cartridge type fuse including in combination a closure unit comprising a grooved cap, an apertured hood integrally formed thereon, an apertured contact member in said cap projecting into the hood, with the apertures in the contact member registering with the groove in the cap, a porous filling in the contact member and in contact with the apertured hood, and an insulation flange secured on the contact member and having one surface thereof provided with a network of escape grooves communicating with the groove in the cap.

13. In a fuse of the class described including in combination a casing closure unit comprising a grooved and apertured cap, a knurled and apertured contact member rigidly secured in the cap, a multi-passaged filler in the contact member, and an insulation flange on the contact member having a network of intersecting grooves therein communicating with the groove in said cap and with the apertures in the contact member.

14. A cartridge type fuse comprising an insulation casing, a threaded thimble secured on one end of the casing, a second thimble for engagement on the opposite end of the casing, and an insulation closure plate in the outer end of the second thimble.

15. A cartridge fuse including in combination a casing, and a closure unit therefor comprising a threaded metal thimble, and an apertured and slotted insulation end closure plate secured in one end of the thimble.

16. In a fuse of the class described including in combination a grooved cap, and a peripherally knurled contact means secured therein and having one surface thereof provided with a network of escape grooves communicating with the cap 10 grooves.

17. In a fuse of the class described including in combination a contact means having a peripherally knurled exterior surface and an outer end surface having a network of escape grooves 15 therein communicating with the grooves in the knurled surface.

18. In a fuse of the class described including in combination an apertured cap, a contact means therein having a surface provided with 20 a network of escape grooves, and a porous filling in the cap in contact with the grooved surface of the contact means.

19. A cartridge fuse including in combination a casing comprising a main body portion having 25 threaded end portions integral therewith and provided with notches in the ends of said main body portion adjacent the inner ends of the threaded end portions, threaded thimbles engaged on said threaded end portions, and means 30 integral with the inner ends of said thimbles and seated in said notches to hold the thimbles locked against rotation.

20. In a fuse, a casing comprising an insulation body including an insulation closure disc 35 integrally formed in one end thereof and having a fuse element slot and gas escape apertures therein, said body having the opposite end open and grooved to provide a stop shoulder, and a flanged, slotted and apertured insulation closure 40 disc removably engaged in the open end of the body and double seated against said shoulder and against the end of the body.

JOHN B. GLOWACKI.
